United States Patent Office

Des. 218,157

Patented July 28, 1970

218,157

PORTABLE TOILET BUILDING

Logan W. Johnson, Minnetonka, Minn., assignor to
Satellite Service Company, Minneapolis, Minn., a
corporation of Minnesota

Filed July 3, 1969, Ser. No. 18,053

Term of patent 14 years

Int. Cl. D25—04

U.S. Cl. D13—1

FIG. 1

FIG. 2

FIG. 3

FIG. 4

FIG. 1 is a front elevational view of a portable toilet building embodying my design;

FIG. 2 is a rear elevational view of said portable toilet building;

FIG. 3 is a right side elevational view of said portable toilet building, the left side view being substantially a mirror image thereof; and

FIG. 4 is a plan view of said portable toilet building.

The bottom is free of ornamentation.

I claim:

The ornamentation design for a portable toilet building, substantially as shown and described.
